US00D581415S

(12) **United States Design Patent**
Hengel et al.

(10) **Patent No.:** **US D581,415 S**
(45) **Date of Patent:** **** Nov. 25, 2008**

(54) **COMPUTER MOUSE**

(75) Inventors: **Andy Hengel**, Los Gatos, CA (US);
Peter Sheehan, New Castle County
Wicklow (IE); **Eugene Canavan**, Bray
County Wicklow (IE)

(73) Assignee: **Logitech Europe S.A. (CH)**

(**) Term: **14 Years**

(21) Appl. No.: **29/261,791**

(22) Filed: **Jun. 19, 2006**

(51) **LOC (8) Cl. 14-02**

(52) **U.S. Cl. D14/402**

(58) **Field of Classification Search** D14/402-410,
D14/417; 235/472.01; 345/156-167; 365/49;

(57) **CLAIM**

The ornamental design for computer mouse, as shown and described.

DESCRIPTION

FIG. 1 is a perspective view of a computer mouse showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right elevational view thereof; and,

FIG. 7 is a left elevational view thereof.

Phantom lining, where utilized, is for illustrative purposes only, and is not intended to limit the claimed component design to the features shown in phantom.

1 Claim, 3 Drawing Sheets
